Joseph Meilner, West Orange, N. J., assignor to Eagle Pencil Company, New York, N. Y., a corporation of Delaware

Application April 2, 1936, Serial No. 61,912

Term of patent 14 years

To all whom it may concern:

Be it known that I, Joseph Meilner, a citizen of the Republic of Germany, residing at 20 William Street, West Orange, State of New Jersey, United States of America, have invented a new,
original, and ornamental Design for a Compass, of which the following is a specification, reference being had to the accompanying drawing, forming part thereof.

Fig. 1 is a front elevation of the compass embodying the present invention; and

Fig. 2 is a top plan view of said compass.

I claim:

The ornamental design for a compass as shown.

JOSEPH MEILNER.
